UNITED STATES PATENT OFFICE.

ANDREW BAKER, OF SPRING VALLEY, NEW YORK.

CLEANER ATTACHMENT FOR SILK-THROWING MACHINES.

1,275,361.

Specification of Letters Patent. Patented Aug. 13, 1918.

Application filed March 17, 1917. Serial No. 155,458.

To all whom it may concern:

Be it known that I, ANDREW BAKER, a citizen of the United States, and a resident of Spring Valley, in the county of Rockland 5 and State of New York, have invented a new and Improved Cleaner Attachment for Silk-Throwing Machines, of which the following is a full, clear, and exact description.

My invention is particularly intended for 10 use on a silk-throwing machine to remove from the silk threads the bunches of waste or like particles adhering to the threads.

Objects of the invention are to provide a 15 cleaner attachment, adapted to be secured to the cross piece running through the silk-throwing machine below the upper bobbins, and provided with combs disposed horizontally, transverse to the path of movement of the threads; and to provide a cleaner attachment 20 having a comb so formed as to avoid all danger of the breaking of the silk threads, except when a bunch of waste or the like is twisted fast in the thread.

The nature of the attachment and its advantages 25 will clearly appear as the description proceeds.

Reference is to be had to the accompanying drawings forming part of this specification in which similar reference characters 30 indicate corresponding parts in all the views.

Figure 1 is a transverse vertical section of a silk-throwing frame having my cleaner attachment applied thereto, the said attachment being shown in side elevation;

35 Fig. 2 is a plan view of the attachment;

Fig. 3 is a plan view of one end of the attachment on a larger scale;

Fig. 4 is a longitudinal vertical section of the parts shown in Fig. 3.

40 The machine illustrated, which is of known form, includes a cross piece A running through the vertical members B of the frame below the upper bobbins C, between the same and the usual drop eyes D, through which the silk threads E run, said threads running 45 also over the rollers F to the lower bobbins G. My improved attachment designated generally by the numeral 10 is adapted to be secured to the cross piece A transversely

50 thereof, the under side of the central body portion of the attachment having a depression to receive the top of said cross piece. The attachment is secured in position by any suitable means, such as bolts 11 having nuts 55 12, the bolts passing through bolt holes 13 in the attachment.

At each end of the attachment is a comb designated generally by the numeral 14, the combs being received in rabbets 15 formed in the ends of the body of the attachment. 60 The arrangement is such that the combs 14 will project at each side of the machine beyond the cross piece A and in the path of the threads E so that the said threads will be caused to pass through the combs between 65 the teeth thereof.

Each comb includes resilient metal teeth 16, the teeth being produced separately in the form of flat metal strips. The teeth are disposed vertically between side fingers 17. 70 To uniformly space the teeth a fine wire 18 is laced over upper and lower pairs of cross bars 19 on the teeth and between said teeth. The wire 18 and cross bars 19 are applied to the teeth a distance in front of the rear ends 75 of the teeth, that is to say, adjacent to the ends of the rabbets 15 in which the teeth are received. The numeral 20 indicates solder, a part of which is broken away in Fig. 4, the solder, in practice, being applied to the 80 teeth from the rear ends to the front transverse bars 19 so as to unite the whole. Rearward of the wire 18 and bars 19 top and bottom plates 21 are applied to the teeth and these may be held in position by the solder 85 20 so that the comb will be in the form of a unitary structure made solid at the inner end thereof. To removably secure the combs in position bolts 22 are employed having nuts 23. With a comb thus formed the teeth 90 will accommodate the threads E between the opposed flat sides of the teeth and will engage the same in a manner to remove any adhering particles without damage or danger of breaking the threads, except when a 95 bunch of waste or the like is twisted fast in the thread.

I wish to state in conclusion that although the illustrated example constitutes a practical embodiment of my invention, I do not 100 limit myself strictly to the mechanical details herein illustrated, since manifestly the same can be considerably varied without departure from the spirit of the invention as defined in the appended claims.

Having thus described my invention, I 105 claim as new, and desire to secure by Letters Patent:

1. The combination with a silk-throwing machine, having a cross piece running 110 through the throwing machine below the upper bobbin spindles, of a cleaner attachment

having a member secured to said cross piece, and having laterally projecting end combs horizontally disposed beyond the said cross bar at the sides of the machine, in the path 5 of movement of the silk threads.

2. A cleaner attachment for silk-throwing machines and the like, including a comb, a support carrying said comb, and means to secure the support to the machine, said comb 10 comprising teeth each formed of a flat re-

silient metal strip, cross bars on the flattened teeth at the upper and lower sides thereof, spacing wires laced about the said transverse bars and between the teeth, upper and lower plates on the teeth at the base thereof rear- 15 ward of the wires and cross bars, and means uniting all the said elements of the comb together.

ANDREW BAKER.

Copies of this patent may be obtained for five cents each, by addressing the "Commissioner of Patents, Washington, D. C."
